SWEATER INSTRUCTION WHEEL

Beatrice L. Freeman, 113 Clemson Road,
Bryn Mawr, Pa. 19010

Filed Dec. 5, 1969, Ser. No. 20,382

Term of patent 14 years
Int. Cl. D19—08

U.S. Cl. D25—1

Fig. 2.

FIG. 1 is a front view showing my new design of sweater instruction wheel, the rear view being substantially identical.

FIG. 2 is a side view showing my new design, all side views being substantially identical.

I claim:

The ornamental design for a sweater instruction wheel, as shown and described.
